UNITED STATES PATENT OFFICE.

CHRISTENNA A. OLIVER, OF PAYNE'S CORNERS, OHIO.

CURTAIN-HANGER.

SPECIFICATION forming part of Letters Patent No. 608,070, dated July 26, 1898.

Application filed August 21, 1897. Serial No. 648,993. (No model.)

To all whom it may concern:

Be it known that I, CHRISTENNA A. OLIVER, of Payne's Corners, in the county of Trumbull and State of Ohio, have invented certain 5 new and useful Improvements in Curtain-Hangers; and I do hereby declare the following to be a full, clear, and exact description of the invention, such as will enable others skilled in the art to which it appertains to 10 make and use the same.

This invention contemplates certain new and useful improvements in curtain hangers or supports.

The primary object of the invention is to 15 provide an extremely simple and inexpensive hanger for lace curtains, which may also serve as the support for shades or roller-curtains.

A further object is to provide a hanger of this character which is capable of being adjusted to accommodate windows and curtains of various sizes.

The invention will be hereinafter fully set forth, and particularly pointed out in the claims.

25 In the accompanying drawings, Figure 1 is a view in perspective illustrating my invention. Fig. 2 is a detail bottom plan view with parts broken away.

Referring to the drawings, A designates the 30 hanger, which consists of the outer sections a, running parallel with the top of the window-frame x, and two end sections a' a² at right angles to said outer section and removably secured at their inner ends to said window-frame.

35 In the drawings I have shown a form of hanger having the outer section a composed of two bars a³ a⁴ to be scopically connected, the longitudinal edges of bar a⁴ hugging the 40 edges of bar a³. The bar a³ at one end is bent inward at right angles to form the end section a', which latter serves as a spring tending to hold the outer free end of said bar away from the window-frame. The extreme inner 45 end a⁵ of section a' is flanged so as to be removably held by a keeper-plate a⁶, attached to the frame x. The outer end of the movable bar a⁴ has a slot a⁷, with which is designed to engage the hooked end a⁸ of the

end section a². This latter consists of a short 50 bar at right angles to the front of frame x and having its inner flanged end a⁹ secured to the latter by a keeper-plate a¹⁰. After a curtain is hung or draped on the outer section a the slot a⁷ is brought into line with hook a⁸, 55 and the latter will securely hold the free end of the bar. In the end section a' is formed an open-ended slot b, while in line therewith in the end section a² is a hole b'. This slot and hole are designed to accommodate the 60 ends of a curtain-roll.

The advantages of my invention are apparent. It will be readily seen that a hanger constructed as herein described is extremely simple and inexpensive. It can be easily secured to or removed from a window-frame 65 and can be adjusted to accommodate windows of various sizes. It will be also observed that the same hanger will serve for supporting roller-shades and that the necessary adjustment to conform to the length of the shade-roller can be readily secured.

I claim as my invention—

1. A hanger composed of an outer telescoping longitudinal bar and right-angular 75 end sections, one of which latter is of spring-like nature and fast with said bar, the outer end of said bar being free and having a slot therein, the other one of said end sections having a hooked end designed to fit in said 80 slot, the spring-like end section serving to hold the free end of said bar normally away from the hooked end of the other section, substantially as set forth.

2. A hanger composed of an outer longitudinal section consisting of a bar bent at right angles to form an end section, a second bar telescoping the former and having a slot in its outer end and a second right angular end section consisting of a bar having an 85 outer hooked end, substantially as set forth.

In testimony whereof I have signed this specification in the presence of two subscribing witnesses.

CHRISTENNA A. OLIVER.
